MACHINE FOR BLOWING SAND INTO MOLDS

Russell W. Taccone, North East, Pa., assignor to
 Taccone Pneumatic Foundry Equipment Corporation, North East, Pa., a corporation of Pennsylvania

Application April 2, 1948, Serial No. 18,589

8 Claims. (Cl. 22—10)

1

This invention relates generally to machines for making molded sand products such as cores and more particularly to machines for blowing sand into molds to make cores and like molded products.

Prior devices force a comparatively small jet of air through the center of a sand holder leaving a large portion of the sand in the sand holder clinging to the walls thereof because of the viscous nature of the sand and used in making cores and other molded products. The bottom of the sand holders generally have a sieve like structure and great difficulty has been experienced in blowing the viscous sand product used in making cores from the sand holder. Inverted V-shaped sand holders have been tried in prior devices but the sand still clings to the side of the holder inasmuch as the jet of air moves centrally thereof. None of these prior machines have provided automatically operated shut-off means for the air. No means has heretofore been provided for fully and sealingly engaging the sand holder automatically with the result that sand was blown in the face of the operator and the machine and the sand holder is formed out of alignment. Furthermore, no means has been provided for evacuating the space in the top of the sand holder during a predetermined portion of the operation. Furthermore, separate air source means has not been provided for providing power and for compression in a core or mold blowing machine. Another of the defects of prior machines is that the sand is forced ahead of the comparatively low pressure jet of air and is not dispersed throughout the mold.

It is, accordingly, an object of my invention to overcome the above and other defects in machines for blowing sand into a mold and it is more particularly an object of my invention to provide a machine for blowing sand into a mold which is simple in construction, automatic in operation, economical in cost, economical in manufacture, efficient in operation, and easy to operate.

Another object of my invention is to provide a machine for blowing sand into a mold which disperses the air throughout the entire area of the sand holder so that the sand and the air move together into the mold.

Another object of my invention is to provide automatic means for shutting off the air supply in a machine for blowing sand into a mold.

Another object of my invention is to provide a novel machine for blowing sand into a mold which compresses the air or fluid therein on each operation thereby requiring a minimum of air

2

pressure in the supply line for efficient operation.

Another object of my invention is to provide a machine for blowing sand into a mold wherein air and sand in a sand holder are inter-mixed before the sand and air move into a mold.

Another object of my invention is to provide novel means for removing trapped air from a sand holder to prevent sand from being blown into the face of the operator along with means for automatically shutting off said means.

Another object of my invention is to provide novel means for controlling air passing to and from a machine for blowing sand into a mold.

Another object of my invention is to provide a machine for blowing sand into a mold having novel means for controlling the opening of a valve for releasing air into a sand holder.

Another object of my invention is to provide a novel spring-suspended swingable sand holder for a machine for blowing sand into a mold.

Another object of my invention is to provide a novel arrangement of check valves in fluid lines for powering and providing air to be compressed in a machine for blowing sand into a mold.

Another object of my invention is to provide a novel arrangement of check valves in the air lines of a machine for blowing sand into a mold to prevent escape of air from the machine at predetermined times.

Another object of my invention is to provide a machine for blowing sand into a mold wherein separate fluid means are provided for powering the device and for providing air for compression therein.

Another object of my invention is to provide novel seating and sealing means in a machine for blowing sand into a mold.

Another object of my invention is to provide yieldable seating means between the seating member of a machine for blowing sand into a mold, a sand holder and a mold.

Another object of my invention is to provide a novel arrangement of assembled parts for a machine for blowing sand into a mold.

Another object of my invention is to provide novel means in a machine for blowing sand into a mold for compressing the air therein.

Another object of my invention is to provide novel means for limiting the amount of air compression and the amount of the opening of the release valve in a machine for blowing sand into a mold.

Other objects of my invention will become evident from the following detailed description,

taken in conjunction with the accompanying drawings, in which

Fig. 1 is a side elevational view of my novel machine for blowing sand into a mold, in an inoperative position;

Fig. 2 is a front elevational view of my novel machine for blowing sand into a mold, in an inoperative position;

Fig. 3 is a transverse vertical sectional view taken through my novel machine for blowing sand into a mold;

Fig. 4 is a fragmentary view of the lower end of my novel machine for blowing sand into a mold in front elevation with parts of the sand holder and its support in section for better illustration;

Fig. 5 is a diagrammatic plan view of my novel machine for blowing sand into a mold with the sand holder swung into a position beneath the sand hopper; and

Fig. 6 is a plan view similar to Fig. 5 with parts thereof broken away showing the sand holder in a position to be engaged by the seating member of my novel machine for blowing sand into a mold and for engaging a mold on the underside thereof.

Referring now to the drawings, Figs. 1, 2 and 3 show a base 1 with a vertically extending, hollow cylindrical member 2 extending upwardly on the back side thereof forming a reservoir for air or other fluid. A bracket 4 is clamped around reservoir 2 by bolt and nut assemblies 5 and the semi-circular shaped portion 6 thereof is engaged by complementary, semi-cylindrical shaped clamp member 7 through bolt and nut assemblies 8 to engage and support a cylindrically shaped member 12. The hollow cylindrical member 2 has an inlet 13 and outlets 14 and 15. The cylindrical member 12 has an inner stepped portion 16 forming a shoulder 18 and an outer shoulder 19 for engaging the bottom of the semi-circular shaped portion 6 of bracket 4 and semi-circular shaped member 7. A piston 20 having a central aperture 21, a peripheral washer 22 in the aperture 21, an outer peripheral washer 23, and a depending skirted portion 24 with external threads 25 formed on the lower end thereof, is disposed for reciprocation in the cylindrical member 12 and is limited in its downward movement by the shoulder 18. A cylindrical plate or wall 26 having peripheral grooved portions 27 and 28 seats on the upper end of the cylindrical member 12 and has a central aperture 29 with a peripheral washer 30, in alignment with the aperture 21 in the piston 20. L-shaped apertures 31 and 32 provide a passageway for fluid to engage the piston 20 and to an upper chamber 33 formed by annular member 34 which seats in the grooved portion 28 of the wall member 26. Cap member 35 has a depending flanged portion 36 forming an L-shaped peripheral groove 37 for seating on the upper end of the annular member 34, and it has a centrally disposed aperture 38 with a peripheral washer 39, in alignment with the apertures 29 and 21 in the wall member 26 and the piston 20, respectively. A piston 40 with a peripheral washer 41 is reciprocable in the annular member 34 and it has a rod 43 and a rod 42 extending upwardly and downwardly therefrom through the apertures 38, 29 and 21, in the cap member 35, wall member 26 and piston 20, respectively. The upper end of rod 43 is threaded at 44 for threadably engaging a stop member 45 and a lock nut 46 to limit the longitudinal movement of the rods 42 and 43 and 75

pistons connected thereto. The stop member 45 seats on an upwardly extending boss 47 on the cap member 35. The rod 42 has a threaded portion 47 on the lower end thereof for threadably engaging a threaded aperture 48 in compression piston 49 which is reciprocable in the skirted portion 24 of the piston 20. The piston 49 has a conventional peripheral washer 50.

Also reciprocable in the skirted portion 24 of the piston 20 is a piston 52 having a longitudinally extending aperture 53, a recessed portion 54, and a reduced, depending portion 55 for receiving the upper end of a coil spring 56. A valve rod 57 extends through the aperture 53 in the piston 52 and through the spring 56 and has formed on the lower end thereof a valve head 59, the piston 52 being held against upward movement by a transverse pin 51 extending through the upper end of the rod 57. The valve head 59 normally engages a tapered seat 60 in the lower portion 61 of a seating member 62 which has a threaded portion 63 for threadable engagement with the lower threaded end 25 of the piston 20 whereby the seating member 62 reciprocates with the piston 20. The seating member 62 has an open cylindrical portion formed by depending flange 64 on the lower end thereof which has an internal peripheral groove 65 for receiving a yieldable sealing member 66 made of rubber or any other suitable yieldable material. The seating member 62 also has a laterally extending housing 67 with a transverse seat 68 in a wall 69 and an apertured webbed portion 70 for journaling the stem 71 of a valve head 72 adapted to sealingly engage the seat 68 in the wall 69. The housing 67 has an outwardly extending portion 73 attached to the flanged end 74 of a fluid line 75 which leads to and is connected to the opening 14 in the reservoir 2. Seating member 62 also has an angularly extending aperture 80 and an angularly projecting portion 81 for receiving the depending flanged portion 82 of a split valve member 83 having transverse passages 84 and a yieldable diaphragm 85 disposed centrally thereof adapted to seat on an upwardly extending seat 86 formed centrally of the valve member 83 when the fluid on the upper side of the valve 83 has a greater pressure than the fluid in the passage 80 in the seating member 62. The aperture 80 is aligned with an aperture 90 in the member 66. Fluid pipes 87, 88 and 89, are connected to apertures 31 and 91 in the wall member 26 and in the cap member 35, respectively, to provide a source of air or other suitable fluid for actuating the pistons 20 and 40. Pipe 89 leads into a conventional control valve 92 manually operated by a handle 93. The control valve 92 is connected with the aperture 32 in the wall member 26 by pipe 94 thereby providing a source of fluid for raising the piston 40. The valve 92 is also connected to the opening 15 in the reservoir 2 by pipe 95 and check valve housing 96. The housing 96 has a conventional check valve 97 therein adapted to sealingly engage the seat 98 therein.

Referring now to Fig. 4, a bracket 100 is secured by any suitable means to stationary cylindrical member 12 and it has an apertured, outwardly extending portion 101 for journaling a sleeve 102 having cylindrical recesses 103 and 104. Shaft 105 is disposed in the recess 104 of the sleeve 102 and it has a reduced portion 106 extending upwardly through the apertured portion 107 in the sleeve 102. A spring 108 is disposed in the recess 103 surrounding the reduced por-

tion 106 of the shaft 104 and it is held in position by a washer 109 and a transverse pin 110 secured to the upper end of the reduced end 106 of the shaft 104. The lower end 111 of the shaft 104 is reduced in size and has a threaded portion 112, for supporting a bracket 113 which has an apertured bossed portion 114 connected to the lower end of the shaft 104 by a threaded member 115 threadably engaging the threaded portion 112 of the reduced end 111. The bracket 113 also has an apertured portion 116 for receiving a cylindrical sand holder 117. The bracket 113 also has an outwardly extending handle 118 for manual rotation thereof. A torsion spring 119 which surrounds the sleeve 102, has the lower end 120 thereof connected to a bracket 121 comprising part of a closing gate member 143 and the upper end 122 thereof connected to an adjustable ring member 124 secured by a locking screw 123. It will thus be seen that the adjustable member 124 may be rotated and adjusted by loosening the locking screw 123 to increase or decrease the tension of the spring 119. The bracket 121 is held in vertical position by the ring 170. The sand holder 117 comprises cylindrical member 150 having a lower flanged portion 125 with apertures 126 and a cone shaped member 127, a yieldable washer 128 being provided between the members 150 and 127 to provide perfect seating of the yieldable sealing member 129 secured to the bottom apertured side 130 of the member 127 by bonding. The members 150 and 127 are connected together by screw members 131 extending through the apertures 126 in the flanged portion 125 of the member 150. I have shown for illustration a suitable mold 132 for forming a core and having apertures 133 aligned with apertures 134 in the sealing member 129 and in the bottom side of the member 127 so that sand in the sand holder 117 may pass through the apertures 134 and 133 and into the mold 132 to form a core or any other suitable molded product. A sand hopper 140 is supported by a bracket 141 extending from bracket 4 and it has an apertured portion 142 adapted to be alternately engaged by the upper end of the sand holder 117 and the spring-urged closing member 143 which automatically closes the apertured portion 142 of the sand hopper 140 when the sand holder 117 is pulled away therefrom and which automatically moves out of closing relationship with the apertured portion 142 of the sand hopper 140 when the sand holder 117 is forceably engaged therewith. The closing member 143 is urged to a closing position by torsion spring 119.

In operation, the mold 132 is disposed on the base 1 of my novel machine and secured in alignment with sand holder 117 and sealing member 129 thereon. The sand holder 117 is then swung by utilization of the handle 118 underneath the sand hopper 140 wherein it is filled with sand especially treated to make it viscous to form cores or molds. After the sand holder 117 is filled, it is returned to its original position over the mold 132 and in alignment with the seating member 62 and the sealing member 66 carried on the underside thereof. A suitable source of compressed air is provided for the reservoir 2 through the inlet 13 which automatically raises the check valve 72 from seat 68 in seating member 62 to permit the seating member 62 and skirted member 24 to be filled with air or other suitable fluid. Likewise air passes through the pipe line 95 past the check valve 97 and through the pipe

94 and aperture 32 to force the piston 40 upwardly in the chamber 33. The valve handle 93 is then brought to an opposite position thereby connecting the air line 95 through the valve member 92 to air lines 89, 88 and 87 whereby air passes through the aperture 91 in the head 35 and the aperture 31 in the wall member 26 to force the pistons 20 and 40, rod 42 and piston 49 downwardly. The skirted piston 20 moves downwardly until it is stopped in its downward movement by the seating of the sealing members 66 and 129 on the sand holder 117 and the mold 132 respectively. The pistons 40 and 49 continue to move downwardly whereby the piston 49 compresses the air in the seating member 62. The piston 49 continues to move downwardly until it engages the upper side of the piston 52, whereupon the piston 52 is moved against the force of the spring 56 and the valve head 59 on the rod 57 is moved from its seat 60 to release the air into the sand holder 117. As the piston 49 moves downwardly, the air will be compressed to a greater pressure than the pressure of the air in the line 75 thereby closing the check valve 72 and permitting the air to remain in the seating member 62. The apertures 80 and 90 leading from the sand holder 117 are closed by the diaphragm 85 through the pressure of the air in the line 87 when the handle 93 is actuated to open the passage of air to the lines 87, 88 and 89. The handle 93 is then actuated to cut off the supply of air to pipes 87, 88 and 89 and pass the air to the pipe 94 and aperture 32 to raise the piston 40 to the position shown in Fig. 4. The diaphragm 85 permits the passage of air through the apertures 80 and 90 thereby permitting air under pressure in the sand holder 117 to escape through apertures 84 when the air supply in pipes 87, 88, and 89 is cut off by the valve 92. The valve head 59 is forced upwardly by spring 56 immediately after the air is released on top of the pistons 20 and 40 respectively. The valve 92 has an exhaust port shown extending from the top side thereof for releasing air above the pistons 20 and 40, respectively, in sequence upon operation of the handle 93. The sand holder 117 is moved away from the mold 132 by spring member 103. The seating member 62 and piston 20 are moved upwardly by the piston 49 which moves with the piston 40 when air passes through the pipe line 94 and apertures 32 in the wall 26. The distance that the valve head 59 moves outwardly from its seat 60 is regulated by the distance which the piston 49 moves downwardly in the cylindrical member 24 and this in turn is regulated by the stop member 45 on the upper end of the rod 43 which engages the abutting surface 47 on the cap member 35 to limit the movement of the piston 49. It will be noted that sufficient air pressure will be maintained in the line 94 and cylinder 33 to maintain the piston 40 in an uppermost position as shown in Fig. 4 because the check valve 97 will prevent the evacuation of air from the line 94 when the pressure in the reservoir 2 is reduced suddenly. My machine is particularly adapted to permit the use of reduced pressures in the supply lines in the operation of my novel sand blowing machine in that it has been found that pressures in the average compressed air line in the shop are not enough to properly blow the viscous sand from a sand holder to a core box or mold.

It will be evident from the foregoing that I have provided a novel machine for blowing viscous sand from sand holders into a mold which

has universal automatic seating means, which completely intermixes the air passing into the sand holder with the sand thereby passing a mixture of air and sand into the mold to completely disperse the sand therein, one which is automatic in operation by merely throwing a lever, which automatically increases the pressure of the air to provide a greatly increased air pressure to blow the sand from a sand holder, and one with novel structural features which makes the machining, assembly, repair and replacement of parts very simple, economical and efficient.

A vertical rack 160 is secured to the side of reservoir 2 and it is engaged by a gear 161 mounted on shaft 162 which is journalled in apertures 163 in bracket 4. The shaft 162 has an outwardly extending square end 164 for engaging a handle 165 shown in Fig. 5. By rotation of the handle 165, the member 12 and associated parts of my machine may be moved vertically to any desired position.

Although I have described my machine as one for blowing sand into molds, it will be evident that when I speak of sand, I mean a sand which is mixed with suitable conventional viscous products to make it into a compact mold.

Various changes may be made in the specific embodiment of my invention without departing from the spirit thereof or from the scope of the appended claims.

What I claim is:

1. A mold blowing machine comprising a vertically disposed cylinder having independent upper and lower chambers, a power piston slideable in said upper chamber, a piston having a depending skirted portion slideable in said lower chamber, a source of air, air lines connecting to the upper ends of said chambers and said source of air, control means in said air lines for controlling the operation of said pistons in said chambers, an apertured wall separating said chambers, a compression piston slideable in the skirted portion of said last mentioned chamber, a piston rod connecting said power piston and said compression piston extending through said apertured wall, a hollow seating member attached to the skirted portion of said piston in said lower chamber having an outlet port therein, a valve in said outlet port in said seating member for opening and closing same, pipe connections from said hollow seating member to said source of air, an apertured piston slideable in said skirted portion of said piston in said lower chamber in opposed relationship to said compression piston slideable therein and engageable by said compression piston, a shaft connecting said apertured piston and said valve, a spring surrounding said shaft urging said apertured piston and valve movable therewith upwardly whereby said valve is urged to a closed position in the outlet port of said seating member, a support for said cylinder, and a sand holder attached to said support swingable into axial alignment with said seating member whereby the movement of said seating member is arrested in its downward movement and said compression piston compresses the air in said seating member obtained from said source of air through connections thereto.

2. A mold blowing machine as set forth in claim 1 wherein said piston rod has an extension extending through the upper end of said cylinder and a vertically adjustable abutting member is attached to the upper end of said

extension, said abutting member engaging the top of said cylinder to limit the downward movement of said compression piston in engagement with said apertured piston, thereby limiting the movement of said valve movable with said apertured piston away from the outlet port in said seating member.

3. A machine for blowing sand into a mold comprising two vertically aligned cylinders, an apertured wall between said cylinders, a power piston slideable in said upper cylinder, a piston having a depending skirted portion slideable in said lower cylinder, a compression piston movable in the skirted portion of said piston in said lower cylinder, a piston rod extending through said apertured wall connecting said power piston and said compression piston, a source of air, air connections between the upper ends of said cylinders and said source of air and control means therein to move said pistons in said upper and lower cylinders, a hollow seating member attached to the skirted portion of said piston in said lower cylinder, a support for said cylinders, a swingable sand holder attached to said support swingable in alignment with said seating member and engageable thereby upon the downward movement thereof to arrest the downward movement thereof, a valve in said seating member for releasing air into said sand holder when the movement of said skirted portion of said piston in said lower cylinder is arrested by said sand holder, connections from said seating member to said source of air, and a valve actuating member attached to said valve engaged by said compression piston upon a predetermined downward movement thereof to open said valve to release air from said seating member to said sand holder when said skirted portion of said piston in said lower cylinder is arrested by said sand holder, said compression piston compressing the air in said seating member prior to the release thereof by the opening of said valve.

4. A machine for blowing sand into a mold as set forth in claim 3 wherein said seating member has an auxiliary passage therein leading from the portion thereof engaged by said seating member, and a check valve is disposed in said passage to automatically release the air in said sand holder after the downward movement of said power piston has been stopped.

5. A machine for blowing sand into a mold comprising a vertical cylindrical member having an intermediate apertured wall defining an upper and a lower chamber, a power piston slideable in said upper chamber, a piston having a depending skirted portion slideable in said lower chamber, a compression piston comparatively smaller than said power piston movable in the skirted portion of said piston in said lower chamber, a piston rod extending through said intermediate apertured wall connecting said power piston and said compression piston, a source of air and connections therefrom to the upper ends of said chambers for moving said pistons downwardly, a connection to the lower end of said upper chamber for moving said power piston upwardly, control means in said connections for passing air into said chambers and exhausting air therefrom to operate said pistons, a hollow seating member connected to the skirted portion of said piston in said lower chamber having an outlet therein in axial alignment with said piston rod, a spring-urged valve in said outlet for opening and closing same, a source of air and con-

nections therefrom to said hollow seating member, a support for said cylindrical member, a sand holder swingably attached to said support and swingable into axial alignment with said seating member for arresting the downward movement of said seating member, and a valve actuating member connected to said valve and extending upwardly into the skirted portion of said piston in said lower chamber engageable by said compression piston upon the downward movement thereof to move said valve to an open position and release air into said sand holder when said seating member and said piston attached thereto are arrested in their downward movement by said sand holder, said compression piston compressing the air in said hollow seating member upon the downward movement thereof prior to the actuation of said valve.

6. A machine for blowing sand into a mold comprising juxtaposed upper and lower cylindrical members, an apertured wall separating said cylindrical members, a power piston slideable in said upper cylindrical member, a piston having a skirted portion slideable in said lower cylindrical member, a compression piston comparatively smaller than said power piston slideable in the skirted portion of said piston in said lower cylindrical member, a piston rod extending through said apertured wall connecting said power piston and said compression piston, a source of air, pipe connections from said source of air to the upper ends of said upper and lower cylindrical members and to the lower end of said upper cylindrical member for reciprocating said pistons in said cylindrical members, control means in said pipe connections for admitting air to the upper ends of said cylindrical members and exhausting air from the lower end of said upper cylindrical member and for admitting air to the lower end of said upper cylindrical member and exhausting air from the upper ends of said cylindrical members, alternately, a hollow seating member attached to the skirted portion of said piston in said lower cylindrical member, a pipe line connecting said source of air to said hollow seating member, an apertured piston slideable in said skirted portion of said piston in said lower cylindrical member in opposed relationship to said compression piston slideable therein, a valve in said seating member in axial alignment with said power and compression pistons for releasing air from said hollow seating member, a shaft connecting said apertured piston and said valve, a spring surrounding said shaft urging said apertured piston towards said compression piston whereby said valve is urged to a closed position, a support for said cylindrical members, and a sand holder swingably attached to said support swingable into axial alignment with said seating member and engageable thereby upon downward movement thereof to arrest the downward movement of said seating member whereby said compression piston engages said apertured piston to move said valve to an open position, said compression piston compressing the air in said hollow seating member prior to the release therefrom upon the opening of said valve.

7. A machine for blowing sand into a mold as set forth in claim 6 wherein said source of air comprises a vertically extending, hollow cylindrical member having compressed air therein to which are attached supporting brackets ver-

tically movable thereon and attached to said cylindrical members to support same.

8. A machine for blowing sand into a mold comprising juxtaposed upper and lower cylindrical members, an apertured wall separating said cylindrical members, a power piston movable in said upper cylindrical member, a piston having a skirted portion slideable in said lower cylindrical member, a compression piston slideable in the skirted portion of said piston in said lower cylindrical member, a piston rod extending through said apertured wall connecting said power piston and said compression piston, said compression piston being comparatively smaller than said power piston, a source of air, pipe connections between said source of air and the upper ends of said cylindrical members and the lower end of said upper cylindrical member to move said pistons in said cylindrical members, control means in said pipe connections for alternately admitting and exhausting air through said connections, a hollow seating member attached to said skirted portion of said piston in said lower cylindrical member having an auxiliary passage extending outwardly from the bottom thereof, a spring-urged valve in the bottom portion of said seating member, valve actuating means connected to said valve engaged by said compression piston upon the downward movement thereof to open said valve, a diaphragm normally spaced from one end of said auxiliary passage in said seating member normally sealingly engaging said passage, a pipe connection from said pipe connections to said cylindrical members to said casing containing said diaphragm for moving said diaphragm to sealingly engage said passage when air moves said power piston downwardly, a support for said cylindrical members, and a swingable sand holder connected to said support and swingable into axial alignment with said seating member for arresting the downward movement thereof whereby said compression piston, after compressing the air in said seating member, continues to move in the skirted portion of said piston in said lower cylindrical member to engage and move said valve actuating means to move said valve in said seating member to an open position to release air into said sand holder, said diaphragm sealingly engaging said auxiliary passage in said seating member moving to an unsealed position when air is exhausted from said upper cylindrical member above said pistons therein.
